UNITED STATES PATENT OFFICE.

PONDER L. PRITCHETT, OF FORT WORTH, TEXAS.

CORD-ADJUSTER FOR ELECTRIC LIGHTS.

1,079,720.

Specification of Letters Patent. Patented Nov. 25, 1913.

Application filed February 11, 1913. Serial No. 747,754.

To all whom it may concern:

Be it known that I, PONDER L. PRITCHETT, a citizen of the United States, residing at Fort Worth, in the county of Tarrant and 5 State of Texas, have invented certain new and useful Improvements in Cord-Adjusters for Electric Lights, of which the following is a specification.

This invention relates to cord adjusters 10 for electric lights, and the object is to provide a simple mechanism for letting out and winding up the wires which connect an electric light globe with the source of power, and to provide a cord long enough to extend 15 to any reasonable length so that the electric light may be placed at different parts of the room or office.

Other objects and advantages will be fully explained in the following description, and 20 the invention will be more particularly pointed out in the claims.

Reference is had to the accompanying drawings which form a part of this application.

25 Figure 1 illustrates an electric light suspended, and shows the hood which connects the cord to the ceiling. Fig. 2 is a section of the inclosing hood, and a section of the guide socket in the hood, and an elevation 30 of the fixtures for winding the cord. Fig. 3 is a side elevation of the circular plate which incloses the operating spring. Fig. 4 is a longitudinal section of the winding spool. Fig. 5 is a detail view of one of the 35 hangers and journal bearing for the spool shaft, showing also two views of a contact making spring. Fig. 6 is a side elevation, and an edge view, respectively, of a circular plate which forms a journal bearing for one 40 of the stub shafts of the spool. Fig. 7 is a detail view of the guide socket mounted in the lower end of the inclosing hood. Fig. 8 is an enlarged detail view of the bar for suspending the spool, and illustrating 45 the electrical connections. Fig. 9 is a plan view of the same.

Similar characters of reference are used to indicate the same parts throughout the several views.

50 This invention is provided with an inclosing hood 1 which is attached to a suspending bar 2 by screws 3. The bar 2 is mounted on the ceiling by a threaded boss 4 which is screwed into a hanger 5 which 55 may be attached to a ceiling in any convenient manner. Bearing arms 6 and 7 for

the winding spool 8 are attached to the bar 2 by means of screws 9 which are insulated from the bar 2 by the insulation bar 10 on top of the bar 2, and the insulation bar 11 60 on the bottom of the bar 2, and by perforated plugs of insulation 12 which are inserted in the bar 2 and the horizontal portions of bearing arms 6 and 7. Electrical connection is made with the hangers 6 and 7, or bearing arms 6 and 7 by means of binding posts 13 which are extended through insulation bars 10 and 11 and the bearing 2, and screwed into the horizontal portions of the hangers 6 and 7. The binding posts 13 are insulated from the bar 2 by perforated plugs 14 of insulation. Wires 15 and 16 are connected to the binding posts 13 which completes the connection from the wires to the hangers 6 and 7. 75 The spool 8 is preferably made of wood. The circular plate 17 is attached to one end of the spool to form a journal bearing. A stub shaft 18, secured to the plate 17, is journaled in the hanger 7. 80

In order to make the electrical connection between hanger 7 and the stub shaft 18 certain, a spring 19 may be attached to the hanger 7 to bear against the end of shaft 18. On the other side of the spool 8 a 85 circular box 20 is carried sunk in the spool, and a circular plate 21 which is attached to the spool forms a cover for the box 20. A stub shaft 22 is provided for that end of the spool 8 and is journaled in the box 20 90 and the circular plate 21 and fixedly secured in the hanger 6. This makes the electrical connection from the wire 15 through the stub shaft 22. An operating spring 23 is attached to the stub shaft 22 95 and to the box 20, as shown in Fig. 4. This spring controls the winding and the unwinding of the cord 24. The electrical connection is completed by connecting the wires 25 and 26 which are inclosed in the cord 24 100 to the stub shafts 22 and 18 respectively, by binding screws 27. The cord 24 enters through a perforation 28 in the side of the spool so that the wires 25 and 26 may be connected to the stub shafts 22 and 18. 105 Gravity dogs 29 are pivotally mounted on the plate 21 and adapted to engage a collar 30 which is rigid with the stub shaft 22, the collar 30 having recesses to be engaged by the dogs 29 as shown in Fig. 3. A 110 guide socket 31 is mounted in the lower part of the hood 1 to form a bearing for

the cord 24, and to prevent electrical connection of the cord with the hood. Any suitable electric lamp may be connected to the cord 24. The spring 23 may be wound 5 in any suitable manner on the stub shaft 22 and attached thereto, and attached to the spring box 20. The cord 24 may be extended whenever desirable by simply pulling on the cord. The gravity dog 29 will 10 hold the cord at any position it may be stopped. When the cord 24 is to be re-wound on the spool 8, a slight pull on the cord 24 will release the dogs 29 so that the spring 23 may re-wind the cord on spool 8.

15 What I claim, is,—

1. A cord adjuster for electric lights having a suspending bar, hangers connected to said bar and insulated therefrom, stub-shafts supported in said hangers, a spool of 20 non-conducting material mounted on said stub shafts, a spring box countersunk in one end of said spool and rigid therewith, a winding spring attached to said box and to the stub shaft, binding posts mounted in 25 said bar and insulated therefrom and electrically connected with said hangers, current wires connected to said binding posts, a cord entering the side of said spool and extending within the spool, and current wires carried 30 by said cord to be connected to an electric lamp, means for holding the lamp in adjustable position, one wire being connected to the stub shaft in one end of the spool, and the other wire being connected to the stub 35 shaft in the other end of said spool.

2. A cord adjuster for electric lights comprising a suspending bar, hangers connected to said bar and insulated therefrom, stub-shafts, one being mounted rigidly in one 40 hanger and the other journaled in the other hanger, and electrically connected therewith, a hollow spool of non-conducting material having a bearing plate countersunk in one end to form a bearing to engage one of said 45 shafts and a spring box countersunk in the other end to form a bearing to engage the other shaft, a spring for winding said spool having one end attached to said box and the

other end attached to the adjacent stub shaft, binding posts mounted in said bar 50 and electrically connected to said hangers, current wires connected to said binding posts, a cord entering the side of said spool, wires carried by said cord and electrically and operatively connected to said stub-shafts, and to be connected to an electric lamp, means for holding the lamp in adjusted position, a hood for said spool attached to said bar, and a guide socket of insulating material forming the outlet of 60 said cord from said hood.

3. A cord adjuster and fixtures therefor comprising a suspending bar, means for connecting said bar to a suitable support, hangers attached to said bar and insulated 65 therefrom, stub-shafts supported in said hangers and electrically connected therewith, a spring attached to one of said hangers and bearing against the adjacent stub-shaft, a hollow spool having a bearing 70 plate countersunk in one end for engaging one of said shafts, a spring box countersunk in the other end of said spool and forming a bearing to engage the other stub-shaft, a spring for winding said spool having one 75 end attached to said box and the other end attached to the adjacent stub-shaft, binding posts mounted in said bar and insulated therefrom and electrically connected with said hangers, a cord entering said spool through the side thereof and wires for connecting with an electric lamp carried by said cord and operatively connected to the ends of said stub-shafts, a hood for inclosing said spool and hangers attached to said bar, and 80 a guide of insulating material mounted in said hood and forming the outlet for said cord.

In testimony whereof, I set my hand in the presence of two witnesses, this 8th day 90 of February, 1913.

POUNDER L. PRITCHETT.
